UNITED STATES PATENT OFFICE.

JOHN J. EAGAN, OF SAN FRANCISCO, CALIFORNIA.

CONCRETE SHIP CONSTRUCTION.

1,373,804.

Specification of Letters Patent.

Patented Apr. 5, 1921.

Application filed June 19, 1920. Serial No. 390,223.

To all whom it may concern:

Be it known that I, JOHN J. EAGAN, a citizen of the United States, residing at the city of San Francisco, in the county of San Francisco and State of California, have invented certain new and useful Improvements in Concrete Ship Construction, of which the following is a specification.

My invention relates to improvements in concrete ships, and particularly improvements in the improved ship construction shown and described in the Letters Patent of the United States issued to me and dated the sixteenth day of September, 1919, bearing Number 1,316,088.

The object of my invention is to produce a concrete hull having improved means of reinforcement, so as to give the same greater strength than heretofore known, and my invention consists in the novel arrangement and combination of parts shown in the accompanying drawings, described in the following specification and particularly pointed out and claimed in the appended claims.

Referring to the accompanying drawings illustrating my invention, so that one skilled in the art to which the invention pertains may make the same, Figure 1 is a side view 30 of the ship embodying my invention, with parts omitted, and parts of said view being broken away to show certain features of the construction; Fig. 2 is a transverse vertical section of the hull; Fig. 3 is an enlarged- 35 detail view of the partition in and side of the hull, and Fig. 4 is a detail showing in what manner the semi-circular tubes hereinafter mentioned are fastened to the transverse ribs.

In the figures A represents a concrete vessel having reinforcements for the hull made of tubular material containing perforations forming the frame as shown; 2 is a central longitudinal tubular member running the 45 length of the vessel forming the keel, the front end of which is bent up, as shown, at 3 to form the stem of the vessel and the rear end of which is also bent up to form the stern of said vessel, as shown at 5.

Running transversely of the vessel at certain intervals and passing through the central tubular member at the bottom are ribs 9, the same being bent up to form side supports for the vessel. Semi-cylindrical reinforcing elements 8 are placed at certain intervals on outer side of ribs 9 and are suit-

ably tied thereto, the same running longitudinally of the shell from bow to stern for the purpose of forming a rigid structure the full length of the ship and said tubes 60 contain cables 10 anchored in the bow and stern for supporting and strengthening said cables. The hull of the vessel is further supported by tubular vertical braces 11 secured in ribs 9 at the bottom of the said 65 hull and upwardly in cross-tube 13, whereby the upper concrete wall 14 of the bottom is supported. By means of the concrete walls 14 and 22 the shell inclosing compartments 12 is formed at the bottom, the dots 70 in the figures indicating concrete as shown at 20.

At certain intervals and spaced from each other are columns 15 mounted in and coupled centrally through the vessel as shown 75 to support the upper and lower decks, 18, and the same are reinforced by means of transverse tubes 16 connected to said central columns 15 and at their ends secured to the ribs 9.

The decks and bottoms have reinforcing tubes 17, running longitudinally through the vessel and suitably secured to brace transverse members 9. The transverse members 9 have ties 23 preferably of wire, which encircle the same and are secured to tubes 8, one of which so secured being shown in Fig. 4. Tubular members 24 run transversely in the partitions shown and the ends thereof are secured in vertical channel bars 26, and are 85 suitably spaced by means of surrounding connected wires 25. In the construction I use slip joints, which I prefer to hold in position by means of pins running through the same as shown at 20'. Also in the construction wire mesh is placed in the hull of the vessel as shown in Figs. 1, 2 and 3, being marked 21, and the same is advantageous as a reinforcement. I prefer to fill the tubular members forming the frame of 95 the vessel together with the bottom and sides of the hull with concrete so as to give the same the utmost strength. It will be understood that the tubular members shown and described will be made in sections and 100 have suitable joints for connecting the same, and that the other parts of the framework will be suitably bolted together so as to give the same the necessary rigidity.

Although I have shown and described the 110 preferred form of my invention, the same may be modified, and therefore I claim all

modifications of said invention which may fall within its spirit and scope.

I claim:

1. In a concrete vessel the framework 5 consisting of U-shaped ribs for the bottom and sides of said vessel, cross-ribs connected to said U-shaped ribs and supporting the decks, pillars between and connected to said cross-ribs, a plurality of pillars between and 10 connected to the lowermost of said cross-ribs and the bottom of said U-shaped ribs, hollow members in contact with the outer surface of said U-shaped ribs, cables extending through said hollow members and secured 15 to the ends of said vessel and wire mesh covering said hollow members.
2. In a concrete vessel the framework consisting of U-shaped ribs for the bottom and sides of said vessel, cross-ribs connected to 20 said U-shaped ribs and supporting the decks, pillars between and connected to said cross-ribs, pillars between and connected to the lowermost of said cross-ribs and the bottom of said U-shaped ribs, hollow members in 25 contact with the outer surface of said U-shaped ribs, cables extending through said hollow members and secured to the ends of the vessel, wire mesh covering said hollow members, and a plurality of equidistant 30 cross-tubes supported between said pillars and between the cross-ribs and pillars nearest thereto.
3. In a concrete vessel the framework consisting of U-shaped ribs for the bottom and 35 sides of said vessel, cross-ribs connected to said U-shaped ribs and supporting the decks, pillars between and connected to said cross-ribs, pillars between and connected to the lowermost of said cross-ribs and the bottom 40 of said U-shaped ribs, hollow members in contact with the outer surface of said U-shaped ribs, cables extending through said hollow members and secured to the ends of the vessel, wire mesh covering said hollow 45 members, a plurality of equidistant cross-

tubes supported between said pillars and between said cross-ribs and pillars nearest thereto, and a centrally placed bent up member forming the keel and front and rear main posts of the vessel and having a cable 50 extending therethrough.

4. In a concrete vessel the framework consisting of U-shaped ribs for the bottom and sides of the vessel, cross-ribs connected to said U-shaped ribs and supporting the decks, 55 pillars between and connected to said cross-ribs, pillars between and connected to the lowermost of said cross-ribs and the bottom of said U-shaped ribs, hollow members in contact with the outer surface of said U-shaped ribs, cables extending through said hollow members and secured to the ends of the vessel, wire mesh covering said hollow members, a plurality of cross-tubes supported 60 between said pillars and between said cross-ribs and pillars nearest thereto, a centrally placed bent up member forming the keel and front and rear main posts, and tubing extending through the decks and wire mesh upon said tubing.

5. In a concrete vessel the framework consisting of U-shaped ribs for the bottom and sides of said vessel, cross-ribs connected to said U-shaped ribs and supporting the decks, pillars between and connected to said cross-ribs, pillars between and connected to the lowermost of said cross-ribs and the bottom 70 of said U-shaped ribs, hollow members secured outwardly to said U-shaped ribs, and cables extending through said hollow members and secured to the ends of the vessel.

6. In combination with the transverse reinforcements of a concrete ship, hollow members in contact with the outside of the transverse reinforcements, cables extending from end to end of the vessel and secured thereto and incased in the hollow members and wire mesh covering the hollow members.

In testimony whereof I affix my signature.
JOHN J. EAGAN.
